UNITED STATES PATENT OFFICE.

LAURENCE E. TOPHAM, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

SEWING MACHINE.

Application filed May 24, 1920. Serial No. 383,634.

The invention relates to wax thread sewing machines such as are used in stitching the out soles of boots and shoes.

The object of the invention is to provide 5 a simple and efficient construction which is well adapted for effecting or permitting a continuous feed of the work during the sewing.

One of the features of the invention consists in back feeding the work support and pressure foot while the needle is out of and the awl is in the work so that any strain 10 incident to the movement of the work support and presser foot in a direction opposite to that of the feed will be resisted by the awl rather than by the needle, with the well 15 recognized advantages usually incident to machines provided with an awl feed as distinguished from a needle feed.

Another feature consists in so mounting 20 the work engaging devices that the needle and awl move together, and the presser foot and work support move together in the line of feed. This permits a simple and compact 25 construction to be utilized which is well adapted for moving the work support and presser foot relatively to the work when either the awl or the needle is in the work.

These features, as well as the further features 30 specified in the claims, will be readily understood from an inspection of the accompanying drawings and the following detailed description of the mechanism illustrated therein.

In the drawings Fig. 1 is a side elevation showing so much of an out sole stitching machine as is necessary to illustrate the application of present invention thereto. Fig. 2 is a front elevation of the parts shown in 35 Fig. 1, Fig. 3 is a plan view, Fig. 4 is a horizontal sectional view through the axis of the stud which supports and carries the needle and awl segments, and Figs. 5, 6, 7 and 8 are views illustrating the mode of 40 operation of the work engaging devices.

The stitch forming and work feeding devices of the machine shown comprise a curved hook needle 2, an awl 4, a looper 6, a thread finger 8, a thread lifter 10, a work 45 support 12, and a presser foot 14. The machine is also provided with the usual hook or shuttle and with the usual take-ups and other devices for controlling and manipulating the thread.

In the construction shown the work engaging devices which comprise the needle, awl, work support and presser foot are mounted to move forward and back in the line of feed in such manner that the feed is continuous. The work support and presser 55 foot are mounted upon a yoke-shaped carrier slide 16, provided with bearing bosses 18, which slide on fixed studs 19 and are connected by the web 20. The slide is provided with two rearwardly projecting 60 arms 22, the ends of which are slotted to embrace and slide on guide blocks 24 mounted on a fixed stud 26. The work support is secured in fixed position on the carrier slide while the presser foot is secured on the forward end of a lever 28, which is pivoted at 30 on the slide, and is operated in the usual manner to lock and release the presser foot during the sewing, and to raise it at the end of the sewing for the removal and insertion 65 of the work. The carrier slide is reciprocated in the line of feed by a lever 32, the rear end of which carries a roll engaging a groove in the cam disk 34, and the forward end of which is connected by a link 36 with the 70 slide. The end of the link is adjustably connected to the lever so that the movement imparted to the carrier slide may be varied in accordance with the length of stitch to be 75 sewed.

The needle and awl are secured in segments 38 and 40 which are mounted to turn about a stud 42. The needle segment is provided with a hub 44 upon which the awl segment 40 is mounted, and the segments 90 are held in position on the stud between a flange 46 on the stud and a flange 48 on the sleeve 50, which carries the needle guide 52. A cap plate 53 is secured to the end of the stud and holds the parts against endwise 95 movement on the stud. The needle guide sleeve and cap plate fit within a fixed bearing 54, which serves to support and guide this end of the stud. The other end of the stud is provided with a screw thread which 100 fits within a screw threaded bearing formed in an arm of the carrier slide 16 and in a bearing cap plate 56. With this construction the stud 42 forms a carrier for the needle and awl and is connected with the carrier slide 105 16 by a screw threaded connection which normally connects the parts to move in unison in the line of feed, but which may be

oscillated to cause or permit relative movement between the needle and awl and the work support and presser foot. The stud is oscillated at proper intervals during the 5 sewing by a gear segment 58, secured on the end of a rockshaft 60, and engaging a gear segment 62 formed on the flange 46 of the stud. The rockshaft is mounted in a bearing 64 in the carrier slide 16, and is rocked 10 by a cam lever 66, the rear end of which carries a roll engaging a cam groove in the cam disk 68, and the forward end of which is connected by a link 70 with an arm 72 on the rockshaft. The link 70 is adjustably 15 connected to the cam lever so that the motion transmitted to the stud 42 may be varied in accordance with the length of stitch being sewed.

The screw thread on the end of the needle 20 and awl carrying stud rigidly unites it with the carrier slide 16 so that during the greater part of the stitch forming cycle the needle, awl, work support, and presser foot move forward together in the direction of 25 the feed. During that period in the stitch forming cycle when the awl and needle are both out of engagement with the work the stud 42 is rocked in a direction and at a speed to quickly back feed the stud, and consequently the needle and awl, from the position indicated in Fig. 5 to the position indicated in Fig. 6, the work support and presser foot meanwhile continuing to advance with the work in the direction of the feed. The 30 parts then move forward together until the carrier slide 16, and consequently the work support and presser foot, are to be back fed, when the stud 42 is rocked in the opposite direction and at such a speed that during 35 the back feed of the carrier slide the stud, and consequently the needle and awl, continue to advance in the direction of feed, and to cause or permit the continued forward feed of the work.

The back feed of the carrier slide may be 40 timed to take place when either the awl or the needle is in the work as may be considered or found most desirable. As indicated in Figs. 7 and 8 the cams which reciprocate the carrier slide 16, and oscillate the stud 42, are so timed that the slide is back fed from the position indicated in Fig. 7 to that indicated in Fig. 8 while the awl is in the work, the pressure of the presser foot being relieved at this point in the cycle to permit 45 the movement of the work support and presser foot in the direction opposite to that in which the work is moving. In this case any tendency of the work to move back with 50 the work support and presser foot is resisted by the awl, and all strain or pressure on the needle tending to bend or deflect it from its proper path is avoided.

The needle and awl segments are oscillated 55 by cam levers 74 and 76, the rear ends of

which are provided with rolls engaging cam grooves in the disks 78 and 68, and the forward ends of which are provided with gear segments engaging teeth on the needle and awl segments, and proportioned and arranged to permit the movements of the needle and awl segments in the line of feed. 70

The needle guide is pressed yieldingly against the work during the passage of the needle therethrough by a rack 80 engaging a gear segment 82 on the needle guard sleeve and operated by a spring 84. The rack is mounted to slide in a guideway formed in the arm 86 which carries the bearing 54 for the needle guide sleeve. 80

While it is preferred to utilize the construction shown and described it will be understood that this construction is not essential to the broader features of the invention and that it may be varied or modified 85 as found desirable or best suited to the construction and mode of operation of any machine in which the invention is to be embodied.

What is claimed is:

1. A sewing machine having, in combination, stitch forming mechanism including a needle, an awl, a work support, and a presser foot, all of which are movable in the line of feed, and means for back feeding the 95 work support and presser foot while the awl is in the work.

2. A sewing machine having, in combination, a needle and an awl mounted to reciprocate back and forth together in the line of feed, and a work support and presser foot mounted to reciprocate back and forth together in the line of feed. 100

3. A sewing machine having, in combination, a needle, an awl mounted to reciprocate 105 in the line of feed, a work support and presser foot mounted to reciprocate in the line of feed, and actuating mechanism for the work support and presser foot, timed to back feed them while the awl is in the work. 110

4. A sewing machine having, in combination, stitch forming mechanism comprising a needle, an awl, a work support, and a presser foot, two carriers on which said parts are mounted, a screw threaded connection between the carriers for connecting them to move in unison, mechanism for reciprocating one of the carriers in the line of feed, and mechanism for oscillating the connection. 115

5. A sewing machine having, in combination, a carrier slide mounted to reciprocate in the line of feed, a work support and a presser foot on the slide, a stud, needle and awl segments mounted on the stud, a screw threaded connection between the stud and slide, and mechanism for reciprocating the slide and oscillating the connection. 125

6. A sewing machine having, in combination, a carrier slide mounted to reciprocate 130

- in the line of feed, a work support and a presser foot on the slide, a stud provided with a screw thread engaging a screw threaded bearing in the slide, needle and awl segments mounted on the stud, mechanism for reciprocating the slide, and mechanism for oscillating the stud. 5
7. A sewing machine having, in combination, a carrier slide mounted to reciprocate in the line of feed, one or more work engaging devices on the slide, a stud, a screw thread connection between the stud and slide, one or more work piercing instruments on the stud, mechanism for reciprocating the slide, and mechanism for oscillating the connection. 10
8. A sewing machine having, in combination, a carrier slide mounted to reciprocate in the line of feed, a stud provided with a screw thread engaging a screw threaded bearing in the slide, one or more work engaging devices on the slide, one or more work engaging devices on the stud, mechanism for reciprocating the slide, and mechanism for oscillating the stud. 15
9. A sewing machine having, in combination, a needle segment carrying a curved hook needle, a concentric sleeve carrying a needle guide, and a spring operated rack engaging teeth on the needle guide sleeve. 20
10. A sewing machine having, in combination, a needle segment carrying a curved hook needle, a stud on which the needle segment is mounted, a sleeve mounted on the stud and carrying a needle guide, a gear segment on the sleeve, a bearing for the sleeve, and a spring operated rack engaging the gear segment. 25
11. A sewing machine having, in combination, stitch forming mechanism including a needle, an awl, a work support and a presser foot, and mechanism for reciprocating the work support and presser foot timed to back feed them while the awl is in the work. 30
12. A sewing machine having, in combination, stitch forming mechanism including a needle, an awl, a work support and a presser foot, all of which are movable in the line of feed, and means for back feeding the work support while the awl is in the work. 35
13. A sewing machine having, in combination, stitch forming mechanism including a needle, an awl, a work support and a presser foot, all of which are movable in the line of feed, and means for back feeding the presser foot while the awl is in the work. 40
14. A sewing machine having, in combination, stitch forming mechanism including a needle, an awl, a work support and a presser foot, and mechanism for reciprocating the work support and a presser foot, all of which are movable in the line of feed, and mechanism for reciprocating the work support and a presser foot being mounted for movement independent of each other in the line of feed. 45
15. A sewing machine having, in combination, stitch forming mechanism including a needle, an awl, a work support and a presser foot, all of which are movable in the line of feed, and mechanism for reciprocating the slide, and mechanism for oscillating the stud. 50
16. A sewing machine having, in combination, an awl and a needle mounted to reciprocate together in the line of feed, and a work support and a presser foot also movable in the line of feed. 55
17. A sewing machine having, in combination, a work support and a presser foot mounted to move back and forth together in the line of feed, an awl movable in the line of feed independently of the work support and presser foot, and a needle also movable in the line of feed. 60
18. A sewing machine having, in combination, a carrier slide mounted to reciprocate in the line of feed, work engaging devices on the slide, mechanism for reciprocating the slide and mechanism for imparting a reciprocation relative to said slide in the line of feed to said work engaging devices. 65
19. A sewing machine having, in combination, a carrier slide mounted to reciprocate in the line of feed, a work support and a presser foot on the slide, a needle, an awl, a carrier for the needle and the awl mounted on the carrier slide, mechanism for reciprocating the slide and mechanism for reciprocating the needle and awl carrier on the slide. 70
20. A sewing machine having, in combination, a carrier slide mounted to reciprocate in the line of feed, a work support and a presser foot on the slide, a stud mounted in the slide, needle and awl segments mounted on the stud, mechanism for reciprocating the slide and mechanism for moving the stud with relation to the slide in the line of feed. 75
21. A sewing machine having, in combination, stitch forming mechanism comprising a needle, an awl, a work support and a presser foot, two carriers on which said parts are mounted, a connection between the carriers to cause one to be moved by the other, mechanism for reciprocating one of the carriers in the line of feed and mechanism for imparting a reciprocation to the carriers relative to each other in the line of feed. 80
